UNITED STATES PATENT OFFICE.

WILLIAM SCOTT, OF MEDFORD, MASSACHUSETTS, ASSIGNOR TO SCOTT MANUFACTURING COMPANY, A CORPORATION OF MASSACHUSETTS.

CARBURETER.

1,006,411.

Specification of Letters Patent. Patented Oct. 17, 1911.

Application filed July 8, 1909. Serial No. 506,493.

To all whom it may concern:

Be it known that I, WILLIAM Scott, a citizen of the United States, residing in Medford, in the county of Middlesex and 5 State of Massachusetts, have invented an Improvement in Carbureters, of which the following description, in connection with the accompanying drawings, is a specification, like letters on the drawings representing 10 ing like parts.

The present invention relates to a carbureter, the purpose of the invention being to arrange the carbureter so as to get the necessary mixture of air and vaporized fuel 15 for proper combustion at all speeds.

In carbureting liquid fuel, the vacuum created by the piston stroke of the engine is depended upon to mix the fuel with the air, and it is obvious, therefore, that the 20 amount of fuel sucked in will be varied by the manipulation of the throttle in controlling the engine speed. In the carbureter as ordinarily constructed, in which the liquid fuel is supplied through a permanently ad- 25 justed nozzle, it is necessary to adjust the valve which controls the orifice of said nozzle so as to obtain sufficient gasoline or other liquid fuel to impregnate the air at the highest speed, the result being that when 30 the speed is cut down the mixture becomes too rich, and the operation of the engine, therefore, defective.

In accordance with the invention, the carbureting chamber, which is provided with an 35 air inlet controlled by an automatic valve adapted to increase the capacity of the air inlet as the vacuum increases, and is also provided with two inlet ducts for the liquid fuel, one of said ducts being provided with 40 means for making a preliminary adjustment in order to supply sufficient fuel to give the proper mixture at low speeds, while the other is variable in capacity, being normally closed, but adapted to open and increase the 45 extent of opening as the vacuum increases, due to the opening of the throttle to speed up the motor.

For convenience in description, I will refer to the fuel as gasoline, and to the two 50 inlets for the fuel as needle valves, and the needles which control the valves as the high speed and low speed needles, respectively.

Figure 1 is a top plan view of the carbureter embodying the invention; Fig. 2 is a

vertical section on the line x^2 of Fig. 1; Fig. 55 3 is a vertical section at right angles to that of Fig. 2, and taken in different planes, as indicated by the section line, x^3 , of Fig. 1.

The carbureter embodying the invention is provided with the float chamber or reservoir a which is supplied with gasoline through the inlet passage a^2 controlled by a tapered valve a^3 shown as connected with the end of a lever a^4 pivoted at a^5 and connected at its opposite end with the float 60 which is arranged to close the valve a^3 when the gasoline stands at the proper level. The float consists, as shown in Fig. 3, of upper and lower members b and b^2 connected together by means of a stem b^3 which is shown 65 as guided at its lower end in a socket in the bottom of the reservoir. The member b^2 is arranged to be of substantially the same specific gravity as that of the gasoline so that when submerged in the gasoline it will 70 practically balance and tend to maintain the valve in whatever position it may be in. This leaves the upper portion b but slightly submerged when the float is in action, and the surface tension of the liquid acting on 75 the said upper member, has a strong tendency to steady the float and prevent the same from oscillating owing to the jarring of the machine. From the float chamber a the fuel passes through a duct c from which 80 it passes, as will be described, into the carbureting chamber d which is herein shown as having a tubular outlet passage d^2 adapted to be coupled directly to the intake of 85 the engine and provided with a butterfly throttle valve d^3 after the usual construction.

The float is so adjusted that the gasoline will normally stand about on a level with the outlet portions of the outlet ducts c^2 95 and c^3 , so that a current of air passing into the carbureting chamber will suck up sufficient gasoline to form the necessary explosive mixture.

The outlet passage c^2 is controlled by a 100 needle valve, the needle e of which will be hereinafter referred to as the low speed needle. The said needle e is provided with a screw threaded portion e^2 and a knurled knob e^3 for adjusting purposes. In adjusting the carbureter the low speed needle is turned until the capacity of the outlet c^2 105 is just sufficient to afford the necessary mix-

ture to supply the engine at the lowest speed at which it is practicable to start and run it. The air is supplied to the carbureting chamber d through an intake passage f which is controlled by an automatic valve g , which is herein shown as a cylindrical valve located in a vertical cylindrical passage g^2 transverse to the inlet passage f . The said valve g is provided with transverse partitions g^3 and g^4 between which the walls are cut away to afford a wide space g^5 , the upper portion of which communicates with a channel g^6 formed underneath a lateral extension g^7 which projects into the carbureting chamber d and normally lies, as shown in Figs. 2 and 3, upon the lower surface of said chamber where the gasoline ducts are located. In this normal position of the valve g , the partition g^3 is above the wall portion of the intake f , so that a small passage is continually open from the intake to the interior of the mixing chamber. The location of the projecting portion g^7 is such, moreover, that the current of air rushing in under the said portion during the suction stroke of the piston is directed past the gasoline orifices, the orifice c^2 , as previously described, being continually open and adjusted to supply sufficient gasoline to impregnate the amount of air admitted through the restricted passage above described. When, however, the suction is increased in response to increased opening of the throttle, the vacuum produced will cause a relative increase of atmospheric pressure which will act on the under side of the partition g^4 , which fits in the lower part of the cylindrical guide passage g^2 and tends to lift the valve g , thus exposing a greater portion of the opening g^5 and increasing the area of the air inlet to the carbureting chamber. The lower end of the guide cylinder g^2 is provided with a vent g^8 to admit atmospheric pressure. Under these conditions, it is necessary to increase the amount of gasoline in order to obtain the proper mixture, and for this purpose the gasoline orifice c^3 which is controlled by the high speed needle h , is arranged to be opened as the valve g rises, it being practicable to connect the high speed needle directly with the valve g , as herein shown. Since the needle h is tapered, it is obvious that the increase in the capacity of the gasoline outlet controlled thereby will be progressively increased as the valve g opens, so that the amount of gasoline supplied will be properly proportioned to the amount of air drawn into the cylinder. Conversely, when the throttle is closed to reduce the speed of the engine, the valve g will correspondingly move back to its normal position, closing the orifice controlled by the high speed needle h , the gasoline being then supplied solely by the orifice controlled by the low speed needle e , so that

the proper mixture is afforded to keep the engine running at a low speed. The lifting effect of the atmospheric pressure on the valve g may, if desired, be varied for adjusting purposes, this being accomplished, as herein shown, by means of a by-pass formed in the side of the casting and shown in full and dotted lines, Fig. 3, one end of said by-pass communicating with the carbureting chamber and the other end with the space below the partition g^4 . Communication is thus varied between the space above the valve where the air is partially exhausted, and the space below the valve which is subjected to atmospheric pressure, thus reducing the effect of the atmospheric pressure to some extent. By providing the said passage i , therefore, with an adjustable valve i^2 , the lifting effect may be varied, as desired.

What I claim is:

1. A carbureter having a carbureting chamber provided with an air inlet and two fuel ducts leading into said chamber, combined with means for making a preliminary adjustment of the capacity of one of said ducts; and means for automatically varying the capacity of the other duct in response to the pressure of the air entering the carbureting chamber.

2. A carbureter having a carbureting chamber provided with an air inlet and two fuel ducts leading into said chamber, combined with means for adjusting the capacity for one of said ducts, said duct, after adjustment, having a constant capacity; means for automatically varying the capacity of the other duct in response to the pressure of the air entering the carburetor chamber; and means for varying the capacity of the outlet from said carbureting chamber.

3. A carbureter having a carbureting chamber provided with inlet and outlet passages; a throttle valve in the outlet passage; an adjustable fuel valve located in the inlet passage, said fuel valve after adjustment having a constant capacity; a valve member controlling the inlet passage to regulate the supply of air drawn into the carbureting chamber, said valve operating automatically to increase the area of the air inlet in response to the piston suction of the engine; a second fuel valve also located in the inlet passage; and means for automatically varying the capacity of said second valve in response to the movement of the valve member controlling the inlet passage.

4. In a carbureter, a carbureting chamber provided with an inlet passage; a valve movable transversely across said inlet passage and located in a cylindrical recess forming part of the carbureting chamber, said valve having a lateral orifice, a portion of which is normally closed by the wall of the cylindrical passage; a gasoline orifice lead-

ing to the carbureting chamber; a tapered needle connected with said valve to vary the capacity of said gasolene orifice in response to the movement of said valve; and a second gasolene orifice the capacity of which is controlled by a fixed needle.

In testimony whereof, I have signed my

name to this specification in the presence of two subscribing witnesses.

WILLIAM SCOTT.
